G. W. FERGUSON

TOY

Filed March 23, 1921

Inventor

George W. Ferguson
by Arnold F. Flocke

Attorney

UNITED STATES PATENT OFFICE.

GEORGE W. FERGUSON, OF MINNEAPOLIS, MINNESOTA.

TOY.

Application filed March 23, 1921. Serial No. 454,975.

To all whom it may concern:

Be it known that I, GEORGE W. FERGUSON, a citizen of the United States, residing at Minneapolis, in the county of Hennepin and State of Minnesota, have invented a new and useful Improvement in Toys, of which the following is a specification.

My invention relates to toys and particularly to the class of toy having a figure mounted on wheels and has for its object to provide an inclined axle and a guide member for causing said figure to pass through various grotesque motions as the toy is drawn about on the floor.

In carrying out my objects I provide a frame member in which is journalled an axle having connected therewith a pair of wheels, said axle having an inclined portion on which is mounted a figure, which figure has a member adapted to slide in a guide formed on said frame so that the figure passes through a number of grotesque motions as the toy is drawn about on the floor.

The full objects and advantages of my invention will appear in connection with the detailed description thereof and are particularly pointed out in the claims.

In the drawings, illustrating the application of my invention in one form:—

Fig. 1 is a front elevational view of one form of my invention.

Fig. 2 is a plan view of the device shown in Fig. 1.

Fig. 3 is a plan view of another form of the invention.

Fig. 4 is an elevational view of the device shown in Figure 3.

Fig. 5 is a plan view of still another form of the invention.

Fig. 6 is a view similar to Figure 5 showing a portion of the same in relatively alternate positions.

Fig. 7 is a detail view of a part of the device shown in Figure 6.

Fig. 8 is a plan view of still another form of the invention.

Fig. 9 is a plan view of still another form of the invention.

Fig. 10 is a detail view showing alternative method of connecting the draw bar to the axle.

Fig. 11 is a perspective detail view showing another method of connecting the frame member of my invention to the axle.

In the forms of the invention shown in

Figures 1 and 2, I employ two wheels 10 and 11 which have rigidly secured to them an axle 12, upon which is journalled a frame member 13. At the forward part of the frame member 13 at 14 is connected a handle 15 by means of which the device may be drawn about on the floor. At the center of axle 12 the same is formed with a relatively inclined portion 15 on which is mounted a figure 16 in the shape of a person having a body 17, and head 18 formed in one piece and pairs of arms 19 and legs 20 pivoted to it in their proper positions. The lower ends of the legs 20 are directly pivoted to the inclined portion 15 of axle 12 and are free to rotate relative to said axle. A depending support 21 rigidly fastened to the body 16 is adapted to slide in a vertical plane on a guide member 22 formed on a depending portion 23 of frame 13. As the toy is drawn about on the floor wheels 10 and 11 are rotated and the figure 16 is given a motion reciprocating from one side of the toy to the other by means of the inclined axle 15. The member 21 and guide 22 serve to hold the toy upright and to guide the same in its motions. As the toy is drawn about on the floor arms 19 of the toy swing in relation to the body 17 thereof thus giving the figure an animated appearance.

In Figures 3 and 4 I show a similar device to that in Figures 1 and 2 with the exception that the rearwardly extending guide member 24 is employed which is directly connected to the frame 13. The figure in this case is in the shape of a duck 25 which has its head 26 loosely pivoted to the same and is rotatably mounted on the inclined axle 15 relative thereto as best indicated in Figure 4. The tail of the duck at 27 is arranged to slide on the guide 24 to support the duck and to guide the movements of the same. As the object is drawn about on the floor the duck is given a wabbling motion such as is characteristic to ducks, its head swinging to either side as the duck advances. The tail 27 is loosely seated on the guide 24 so that the twisting motion of the duck does not cause said member to bind on the guide.

In Figure 9 I show a device having two pairs of wheels 28 and 29 with inclined axles 15 the same as in Figure 3. These axles having single frame 31 mounted on them which terminate in two guides 32 and 33

positioned at the two ends thereof. A pair of ducks 34 and 35 are mounted on these inclined axles 15 similar to the duck 25 in Figure 3. The rear duck has its tail 36 5 slidably mounted on guide 33 while the staple shown in dotted lines in Figure 9 at 37 operates on guide 32 in a manner identical with the guide 36. A loop draw bar 31 pivoted to the axle of the forward set 10 of wheels 28 has formed in it an eye 39 to which may be attached a cord for drawing the toy about on the floor. This toy is similar to that shown in Figures 3 and 4 and represents a pair of ducks chasing each 15 other. When the sets of wheels 28 and 29 have their axes relatively disposed as indicated in Figure 9 the ducks wobble in opposite directions to each other giving a very specific appearance as the toy is operated. 20 In Figures 5 and 6 I show a device similar to that shown in Figures 3 and 4. In this device I employ a figure in the shape of a turtle having a body 40 and a plurality of legs 41, a tail 42 and a head 43 all loosely 25 pivoted to it as is indicated in Figure 7. In this device the guide member is absent and the point of attachment of axle 15 to the body 40 is in advance of the center of 30 gravity of the figure so that the tail 42 of the figure drags upon the floor. The toy is in this manner supported partly on the floor and on the axle 15 and as the same is drawn about said figure goes through similar motions to that of the duck shown in 35 Figure 3 with the additional features of the movable tail and legs. Figure 6 shows the turtle as indicated in Figure 5 in its extreme opposite position with the head and arms swung to opposite sides as indicated. 40 In Figure 10, I show another method of attaching a handle for drawing the device similar to that indicated in Figures 5 and 6. In this figure the body 40 of the turtle as indicated with the head and legs removed 45 therefore to show the particular method of attaching the handle. In this case I use a wire handle 43 which is formed with a loop 44 adapted to pass around the center portion of the inclined axle 15. A cavity 50 formed on the underside of the body 40 of the turtle serves to hold the loop 44 in its center position upon the axle 15. As the toy is drawn about by means of handle 43 the wheels 10 and 11 may either one ad- 55 vance ahead of the other dependent upon the friction of the floor against said wheels and the force necessary to move the turtle through the various movements so that the toy is given various additional movements 60 in place with the form of the invention shown in Figures 5 and 6.

In Figure 8, I show another form of the invention which comprises wheels 10 and 11, an inclined axle 15 and a handle 16 with a 65 loop frame 14 for drawing the same, all

similar to the device shown in Figure 6. On the inclined axle 15 I mount a figure representing a snake having a head 46 pivoted thereto with a plurality of body sections 47 each loosely linked to the other by 70 means of pairs of eyes 48 and 49 interlocking each other and secured to said body members and to the head 46. As this device is drawn about on the floor snake takes positions varying between that shown in full 75 lines and dotted lines in Figure 8 passing through motions identically with those of a snake crawling along the floor. In this form of the invention the head portion 46 and the nearest portion 47 to it are raised 80 from the floor while the remainder of the body portions 47 lie on the floor and pass through the serpent like motion indicated.

In Figure 11, I show another method of mounting the wheels on the frame of the device which may be used in conjunction with the forms of the invention shown either in Figure 6 or 8. The axle 15 and wheels 11 and 10 are the same although the frame member 14 is provided with elongated slot- 90 ted portions 48 and 49 which are adapted to slide on the portions 12 of the axle so that the entire toy may advance or retreat along said slots thereby giving the figure mounted thereon certain movements not attainable 95 with the plane connection of the frame to the axle as indicated in either Figure 6 or 8. With this form of the device the movements of the figure are distinctly more erratic than in any of the other forms and 100 are not as regular in occurrence.

The advantages of my invention are manifest, and lie primarily in the extreme simplicity of the device together with the spectacular appearance of the toy as the figure 105 mounted on it goes through its various motions so characteristic to the animal or object it represents. The toy itself may be painted up so as to be highly attractive even when not in operation, which together with 110 the animation given it when the object is operated make it a most attractive and pleasing toy. The toy is furthermore very instructive as the motions given the animals or figures mounted thereon are very imitative 115 of the characteristics of these animals or objects. There is practically nothing to get out of order on the toy and the same can be constructed at a very small cost.

In accordance with the patent statutes I 120 have described the principles of operation of my invention, together with the apparatus which I now consider to represent the best embodiment thereof, but I desire to have it understood that the construction shown is only illustrative and that the invention can be carried out by other means and applied to uses other than those above set forth within the scope of the following 125 claims.

I claim:

1. A toy comprising a pair of wheels having coincident axes, an axle connecting said wheels, having portions coincident with said axes so as to permit the same to rotate at all times perpendicular to the surface supporting the same, and another portion inclined relative thereto, a figure pivoted to said inclined axle portion and means pivoted to said coincident axle portion for supporting and guiding said figure in its movements.
2. A toy comprising a pair of wheels, an axle connecting said wheels, said axle having its ends fixed centrally of said wheels with a portion extending in axial alinement between said wheels, an inclined portion extending between said portion extending in axial alinement with said wheels, a figure having a body portion supported on and pivoted to said inclined axle portion and a member connected with and issuing outwardly from said body portion for partially supporting and guiding at its extreme end said body in its movements.
3. A toy comprising plurality of wheels, an axle having its axis coinciding with the center of said wheels, a relatively inclined portion formed on said axle, a frame journaled on the centrally disposed portion of said axle, a figure pivotally connected to said inclined portion of said axle, a guide attached to said frame and means connected to said figure adapted to operate upon the

said guide to permit the figure to move relative to the frame.

4. A toy comprising plurality of wheels, an axle having its axis coinciding with the center of said wheels, a relatively inclined portion formed on said axle, a frame journaled on the centrally disposed portion of said axle, a figure pivotally connected to said inclined portion of said axle, a guide attached to said frame and means connected to said figure adapted to operate upon the said guide to permit the figure to move relative to the frame, and means connected to said frame for drawing the figure.

5. A toy comprising a plurality of wheels, an inclined axle connecting said wheels, a figure pivotally mounted on said inclined axle, a frame journaled concentrically relative to said wheels, a guide member connected to said frame lying substantially in the plane of said figure and means connected with said figure operating on said guide to permit the figure to move relative to the frame in the plane of said guide.

6. A toy comprising a pair of wheels, an axle fastened to said wheels, a frame journaled on said axle, said axle having an inclined portion at the center thereof, a figure supported on and pivotally connected to said inclined portion and means for movably holding said figure connected to said frame.

In testimony whereof I affix my signature.

GEORGE W. FERGUSON.
